Application April 10, 1946, Serial No. 123,434

(Cl. D26—14)

To all whom it may concern:

Be it known that I, Louis Kniep, Jr., a citizen of the United States, residing at 136A South Munn Avenue, East Orange, Essex County, and State of New Jersey, have invented a new, original, and ornamental Design for a Control Desk, of which the following is a specification, reference being had to the accompanying drawing, forming part thereof.

Fig. 1 is a left-hand perspective view of a control desk, showing my new design; and

Fig. 2 is a rear view of the desk.

A right-hand perspective view of the desk would present substantially the same appearance as the left-hand perspective shown in Fig. 1.

The dominant features of my design reside in the portions shown in full lines.

I claim:

The ornamental design for a control desk, as shown and described.

LOUIS KNIEP, JR.
